PRINTING MACHINE

Carl A. Flood, Framingham, Mass., assignor to
Dennison Manufacturing Company, Framing-
ham, Mass., a corporation of Massachusetts

Application October 25, 1933, Serial No. 695,116

10 Claims. (Cl. 101—96)

This invention relates to an improved machine for printing sheet articles, and more particularly price tickets for use in stores or the like. Tickets of this character are ordinarily provided with a plurality of descriptive and/or identifying characters to indicate the lot number, quality, source of supply, and the like, as well as readily readable indicia to show the retail price, color, size, etc.

The present invention affords improvements in a machine of this character which particularly facilitate the printing of price tickets and in general afford more advantageous arrangements of the general type of mechanism disclosed in my copending application Serial No. 652,468, filed January 19, 1933. In accordance with that invention, a plurality of printing wheels may be interconnected with a plurality of corresponding indicating wheels, one indicating wheel being adjustable simultaneously with a corresponding printing wheel to permit the definite location of the printing symbols in a desired order or arrangement to afford the code indications of price, size, etc. The present invention affords improvements facilitating the proper setting of these printing wheels, and in general facilitating the employment of a machine of this character, particularly when used in printing price tickets for retail stores or for similar purposes.

Price tickets are ordinarily printed in lots corresponding in number to the articles, such as garments, in a lot which is being marked for sale. A machine of the type disclosed herein may be power driven and may be effective rapidly to print separate price tickets, each of which may bear a single set of symbols, or each of which comprises a plurality of sections with similar groups of symbols impressed upon each section. To facilitate the printing of tickets in lots each consisting of a definite number of tickets of this type, the machine is provided with an automatic stop arrangement which is adjustable to permit a selected number of printing operations to be performed, and then is automatically effective to stop printing; thus necessity of the operator counting the number of tickets printed is avoided, and the operator may take full advantage of the rapidity of printing permitted by the machine, while the machine is readily adaptable to print only one or two tickets with the same indicia thereon, if desired. Furthermore, this arrangement avoids the liability of the operator of the machine printing an unnecessarily large number of tickets for a given lot of merchandise and consequent wasting of the tickets.

This invention affords a machine which is par-

ticularly adapted to print tickets or tags of the type which each have a looped string attached at one of its ends. A guide and retainer is provided to receive the string loops and to engage the knotted ends of the latter as they pass away from the platen, thus to hold the tickets in place without necessity for providing a receiving basket or the like for the printed tickets. In a machine of this type tickets may be stacked in a hopper, from the lower part of which they are fed between the printing platen and printing wheels. When tickets having looped strings at their ends are thus stacked in the hopper, the strings tend to interfere with the even stacking of the tickets, and accordingly I have provided vibratory means to assure the proper disposition of the tickets as they reach the bottom of the hopper so that the lowermost ticket is properly located to be engaged by the feeding means and fed between the platen and printing wheels.

Tickets which are employed for identifying articles of merchandise, and to afford an indication of price, ordinarily bear indications of size, quality, and source, which are desirably retained with the article until sold. On the other hand, the retail prices marked upon the tickets are often altered to conform with seasonal trends, changes in style, and other merchandising considerations. The present invention affords a unique arrangement of printing to permit the price indication to be arranged so that the part of the ticket bearing the same may be severed from the remainder of the ticket and a new price disposed in a blank space adjoining this severed end portion. For this purpose a machine of the type shown in my copending application Serial No. 704,137, filed December 27, 1933, may be employed automatically to cut off the printed end of the ticket affording the price indication and also to print the new price upon the body portion of the ticket adjoining its severed end, or such a machine may be arranged to mark a line through the first price indication at the end of the ticket and print a new price adjoining the canceled indication. To permit these desirable results and to permit a relatively compact and convenient arrangement of the indicia upon the ticket, the line of characters indicating the price preferably is disposed transversely in relation to the line or lines of characters affording the information which is desired to be permanently retained on the tag as long as the article is on sale. For this purpose, I preferably provide auxiliary printing wheels and corresponding indicating wheels which are arranged to rotate about axes that are disposed in

planes at right angles to the axis of the main printing and indicating wheels. To facilitate the adjustment of the price indicating wheels, special means is afforded to permit a control shaft to be moved to adjust any one of the auxiliary printing wheels and the corresponding indicating wheel. Furthermore, means of this general type may be employed with the main printing wheels to facilitate the stopping of the wheels in proper position to assure accurate alignment of the characters upon adjoining wheels.

Figs. 19 and 20 are diagrammatic details showing different positions of the control member or pawl and the ratchet bar of the adjusting carriage.

The improvements afforded by this invention may be employed with various types of printing machines, but are particularly applicable to employment with and are illustrated in conjunction with a machine of the same type as disclosed in my copending application Serial No. 652,468, filed January 19, 1933, which is incorporated herewith by reference. Since the detailed arrangement of the mechanism for feeding the tickets and causing oscillatory movement of the platen as well as the clutch means through which these parts are driven are fully described in my copending application, a general description of these parts will be sufficient to permit an understanding of the present invention.

A machine of this type is provided with a suitable frame 1 supporting a driving motor 2 which may be connected through worm gearing 3 to a

pawl clutch 4 adapted to drive a main shaft 5, the latter operating suitable linkage L to cause the platen plate or frame 37 to swing about its pivot 40 and to cause feeding fingers 80 to feed successive tickets or successive ticket sections beneath the platen block 44. The latter is moved downwardly to press the ticket against a printing ribbon 160 which is disposed over a plurality of printing wheels. Disposed on the frame 37 is a hopper provided by the angle bars 251 and the plate 252 which is adapted to be adjusted away from and toward the angles 251 to permit the hopper to accommodate tickets of different sizes; a weight 253 may rest on tickets in the hopper yieldably to press them downwardly. The clutch 15 mechanism 4 is controlled by a throw-out shaft 22 which is connected to suitable control means that will be described in detail. The ribbon 160 may be fed back and forth over the printing wheels by any suitable mechanism, such as that disclosed and described in my copending application Serial No. 652,468, filed January 19, 1933.

The printing wheel assembly which is disposed below platen 44 is in many essential respects of the same general type as that disclosed in that application. For this purpose supporting brackets 100 carry an arbor member 103 (Fig. 17) extending therebetween. Member 103 is in the general form of a casting having a cross section of substantially C-shape (Fig. 8) with its ends 30 providing generally cylindrical bearing surfaces. Upon the bearing surface at one end of member 103 are a plurality of main printing wheels 105 each having internal teeth 106 in bearing engagement with the cylindrical surface of the arbor, 35 while a corresponding number of indicating wheels 110 with internal teeth 111 are mounted at the opposite end of the arbor 103.

A slideable carriage or adjusting mechanism, designated in general by symbol C is mounted in 40 the portion of the arbor where the cylindrical bearing surfaces are discontinued. The arbor provides guideways or grooves on which the carriage frame 115 may slide. A shaft 117 is rotatably supported by journals on the frame 115 and 45 carries a knurled or corrugated adjusting handle or knob 119 at its outer end. Spaced, toothed control wheels 120 and 121 are mounted on the shaft in such a position that the teeth of gear 120 50 may engage the internal teeth of a printing wheel 105 when wheel 121 engages the internal teeth of the corresponding indicating wheel 110. A pointer 140 is fixed to the carriage C in such a manner that its end portion is disposed over the indicating wheel which is being engaged with the corresponding control pinion 121. A suitable transparent cover 146 permits portions of the peripheral surfaces of the indicating wheels to be readily visible, and dark lines or bars 146^a extending 60 across this transparent sheet 146 define an area corresponding to the region upon the surfaces of the printing wheels which are in printing position. Thus the operator by observing the position of the symbols between the line elements 146^a may 65 receive an accurate indication of the relative position of the symbols or printing elements in printing position on the printing wheels.

The carriage C may be moved laterally to bring the pinions 120 and 121 into engagement with 70 the internal teeth of corresponding selected printing and indicating wheels. Ribs or aligning elements 129 on the frame 115 are engageable between the aligned teeth of successive wheels, thus to lock all of the wheels in a fixed or a set posi- 75

tion except the wheels that are being engaged by gears 120 and 121.

In order to facilitate movement of the carriage C and its proper positioning, a rigid bar 130 is provided having upper and lower sets of teeth which may be successively engaged by the stepping pawl 131. This pawl is of the form of a sheet metal member pivotally connected to the end of the carriage frame (Fig. 18) and normally urged in an anticlockwise direction by a spring 128. The member 131 has a bifurcated portion providing outstanding beveled elements which are engageable with the upper and lower sets of teeth on ratchet bar 130. Normally the spring 128 is effective in holding the lower arm of the bifurcated portion in engagement with one of the teeth on the lower edge of bar 130 as shown in Fig. 19. The lower portion of member 131 affords an outstanding flange or handle element 133 which may be pressed downwardly to swing the member 131 against the tension of spring 128, thus disengaging the lower arm of that member from the lower edge of bar 130. Continued downward movement of the finger element 133 causes the upper arm on member 131 to engage the upper toothed edge of bar 130. The bifurcated portion of the member 131 is so shaped and arranged in relation to the teeth of bar 130 that this results in moving the bar 130 and consequently the entire carriage C one half step toward the right as viewed in Figs. 19 and 20. When the finger piece 133 is released, the spring 128 returns member 131 to its normal position, the lower arm of this member being effective in causing the ratchet bar 130 to move toward the right for a second half step. Thus each time that the element 133 is fully depressed and released, a stepped movement of the carriage to the right moves the gears or pinions 120 and 121 out of engagement with a corresponding printing and indicating wheel, respectively, into engagement with the internal teeth upon the next adjoining wheels at the right of the wheels previously engaged.

When it is desired to move the carriage C to the left, a second finger piece 134 is moved upwardly until a shoulder thereon engages a corner of pawl 131 which is pressed downwardly, as shown in Fig. 18. Thus, as the finger pieces 133 and 134 are moved toward each other the member 131 is disposed in the neutral position illustrated in Fig. 18, so that both its upper and lower arms are disengaged from the toothed upper and lower edges of the bar 130. Under these conditions the carriage C is free to slide so that it may be moved manually toward the left to bring the pointer to the desired position, whereupon the finger pieces 133 and 134 may be released, the latter dropping under the action of gravity to its normal position out of engagement with the pawl 131 and the latter moving in an anticlockwise direction under the tension of spring 128, thus to cause the lower arm of member 131 again to move into locking engagement with the ratchet bar 130. When the carriage moves to the right end of its path, as indicated in Fig. 2, control wheels 120 and 121 are located out of engagement with the internal teeth of the printing and indicating wheels and these wheels are held in fixed position in relation to each other by the locking bars 129.

In order to assist in stopping the control wheels so that the adjoining symbols on the printing and indicating wheels are located in definite rows in alignment with each other, mechanism of the type illustrated in Figs. 14 and 15 is disposed at the end of the carriage C. For this purpose a

wheel 41 is secured to the shaft 117 and has shallow teeth upon its periphery, a swinging pawl member 42 being pivotally mounted upon the end plate of the carriage frame and carrying a pin 43 engageable with the toothed periphery of wheel 41. A tension spring 46 is arranged to press the pin against the periphery of the wheel. The teeth of the wheel are shaped so that they engage the pin with a cam-like action permitting the ready movement of the teeth past the pin, but allowing the tension spring 46 to move the pin inwardly so that the wheel tends to stop with the pin located in one of the depressions between adjoining teeth. The teeth and depressions on the wheel 41 are so arranged that the knob 119 and the shaft 117 will tend to stop when the printing wheel that is being adjusted stops with a symbol in definite alignment with the symbols of adjoining printing wheels. Thus the movement of the carriage C is facilitated since the internal teeth 106 and 111 of the printing and indicating wheels will be in definite alignment; thus movement of the carriage into successive positions to effect the adjustment of different printing wheels is facilitated and it is not necessary for the operator to employ precise care in accurately locating the symbols upon the indicating wheel in alignment to permit the movement of the carriage for the adjustment of an adjoining wheel.

In accordance with this invention, an auxiliary printing wheel assembly A is provided to effect the printing of prices upon the ends of the tickets, the single line of printing afforded by the auxiliary mechanism extending at right angles to the line or lines of printing provided by the main printing wheels 105. The general arrangement of the auxiliary mechanism A is shown in Figs. 2 and 3, while Figs. 8 to 13^a inclusive illustrate this assembly in greater detail. The assembly A may include a supporting frame 50 secured upon the arbor 103 and providing end plates through which an adjusting shaft 51 extends. The end of this shaft projects beyond the main printing wheel assembly and carries a knurled control knob or handle 52. The shaft 51 is provided with a plurality of circumferential grooves 53 (Fig. 9), which are engageable with the rounded end of a spring-pressed plunger 54, thus tending to cause the shaft 51 to stop in one of a selected number of adjusted positions when it is slid longitudinally in relation to the fixed frame 50. The inner end of shaft 51 carries a gear wheel 57 fixed thereto. The teeth upon wheel 57 mesh with teeth upon an adjoining gear wheel 58 which is secured to the shaft 59 associated with the indicating wheels 60, and with the gear 62 associated with the auxiliary printing wheels.

As shown in Fig. 11, a bushing or sleeve 64 is disposed about the shaft 59 and engages one face of the wheel 58, the opposite face of which is engaged by a washer 67 secured upon the inner end of shaft 59. The teeth of gear 57 which mesh with gear 58 are disposed between washer 67 and the end of bushing 64 so that longitudinal movement of the shaft 51 and its gear 57 is effective in causing the sliding of bushing 64 in the frame 51. Secured to the shaft 59 is a disk or wheel 69 carrying an outstanding projection 70 which is engageable in internal recesses between teeth on the indicating wheels 60 which are of the general shape shown in Fig. 13. A bushing 71 is disposed between the front surface of wheel 69 and a head 76 on shaft 59. The bushings 64 and 71 each carry aligned ribs which are slidable in engagement with recesses in frame 50 and the indicat-

ing wheels 60 to lock these wheels in position aside from the wheel, that is, in engagement with the projection on adjusting wheel 68. A pointer bar 73 is secured to the bushing 70 and extends over the indicating wheels. Thus as the shaft 51 is longitudinally adjusted it tends to move to a position wherein the plunger 84 engages one of the grooves 63, thus being effective in positioning shaft 59 so that projection 70 may engage one of the indicating wheels 60 to permit the adjustment of the latter.

The printing wheels 74 are arranged about the shaft 89 in the same general manner as has been described in connection with the indicating wheels so that the printing wheels may be adjusted to bring the desired combination of symbols to printing position when the indicating wheels are adjusted to bring the corresponding symbols upon their peripheries to a position under the pointer bar 73 which is secured to the bushing 64.

The arrangement of the auxiliary printing wheels is shown more particularly in Fig. 9, bushings 82 and 83 being disposed about the shaft 84 upon which gear 62 is fixed. These bushings have suitable outsanding ribs slidable in recessed portions of the frame 50 and in the recessed portions of the printing wheels to hold the latter in position, except for the wheel that is in engagement with the projection upon the adjusting disk 87 which is similar in construction to the wheel or disk 69. The teeth of gear 57 which mesh with the teeth of gear 62 are disposed between the bushing 82 and a washer 88. Accordingly, longitudinal movement of shaft 51 with its gear 57 is effective in causing a similar movement of both shafts 59 and 84, causing a corresponding movement of the adjusting wheels 69 and 87 into engagement with corresponding indicating and printing wheels.

Thus to adjust the machine so that a desired price may be printed, the control handle 52 is manipulated to cause the indicating wheels and corresponding printing wheels to be turned in succession until the desired symbols corresponding to the price to be printed are disposed, as shown in Fig. 16, beside the pointer bar 73.

A spring-pressed pawl member 90 is provided with an elongate cam-like ridge or lug 91 to engage the teeth upon gear 57 in any of its adjusted positions (Figs. 10 and 16). A suitable spring is effective in urging this lug into yieldable engagement with the teeth. Thus as the shaft 51 is rotated by manipulation of handle 52, the gear 57 tends to stop in a position wherein the lug on pawl 90 is disposed between its teeth, the arrangement being so determined that the printing wheel which is being adjusted will stop with its symbols in definite alignment with the symbols upon the adjoining wheels that are locked in position by the rib elements in bushings 82 and 83. Thus proper alignment of the symbols upon each of the auxiliary printing wheels is assured.

In order to permit the printing of a definite number of tickets with a selected arrangement of symbols thereon, the automatic stopping and control mechanism S is provided in conjunction with the clutch control shaft or rod 22. This mechanism comprises a fixed bracket 150 secured to the upper part of the frame of the machine and a rotatable drum 152 provided with a knurled peripheral portion and with a plurality of numbers arranged in adjoining parallel rows or peripheral columns. Adjoining the bracket 150 the numbers may be arranged in close sequence, while in the adjoining row the numbers may be sepa-

rated by alternate blank spaces. In the next or third row the numbers may be separated by two blank spaces, while in the fourth row adjoining the knurled portion 153 the numbers may be separated by three spaces.

The bracket 150 supports an arm or cross member 156 in front of the drum 152 bearing numerals "1", "2", "3", and "4" to identify the columns or rows of figures upon the drum 152 (Fig. 2). A red or conspicuously colored signal element 155 bearing the word "Stop" is fixed to the periphery of the drum. When it is desired to print a definite number of tickets, the drum 152 is adjusted so that the portion marked "Stop" will move into registration with the upper edge of the part 155 when the desired number of tickets are printed. Accordingly, the adjustable drum 152 is first set with a number thereon registering with the upper edge of member 156 corresponding to the number of tickets that it is desired to print. If tickets having but a single group of symbols thereon are to be printed, this adjustment is made with reference to the first row or single spaced figures. If tickets each having two sets or groups of symbols are to be printed, the adjustment is made with reference to the second column or double spaced numerals upon the drum. If tickets having three sections are to be printed, the third column is employed to facilitate adjustment, and similarly if tickets having four sections are to be printed, the fourth column is referred to for purposes of adjustment.

Disposed within the bracket 150 is a gear or toothed wheel 159 fixed to the drum 152, which is mounted on the axial bolt 161. A link 163 connected to the platen frame 37 (Fig. 5) extends through an opening in the front of bracket 150 and has a corner portion engageable with successive teeth upon the wheel 159 so that each oscillation of the platen frame 37 which corresponds to a single printing operation is effective in causing the stepped movement of the wheel 159 for a distance corresponding to one tooth upon its periphery. In order to prevent overrunning of the wheel 160, a spring-pressed pawl or detent 162 is provided. A pin 164 mounted on the gear drum 152 is engageable with a block 165 that is connected to a handle member 174 and a rod 176, the latter being connected to the clutch control rod 22. Accordingly, when the pin engages the block 165 the rod 22 is operated to disengage the clutch 4 so that the driving motor 2 may continue to operate without causing further impressions by the platen 44.

When it is desired to cause a further number of printing operations after adjustment of the drum 152, the member 174 is pressed inwardly to cause the reengagement of the clutch mechanism, whereupon the desired number of printing operations may be effected. A bell crank member 177 is loosely mounted on the shaft 161 and is engageable with a pin on the block 165. Accordingly when the clutch is disengaged, the crank 177 is effective in throwing the link 163 upwardly out of engagement with the toothed periphery of wheel 160, thus to permit drum 152 to be manually rotatable in either direction, as may be more convenient.

A link 178 (Figs. 2 and 3) is pivotally connected to a fixed portion of the machine and has an inverted end resting against the inner face of the front portion of the platen frame 37 and accordingly has a sliding movement in engagement therewith as the platen oscillates about its pivotal support 40. An oscillatory member 49 is

disposed adjoining one of the hopper angles 251 and provides a flange disposed adjoining the end flange of this angle. The inturned flange upon link 178 engages an extension of the member 49 5 to cause a limited oscillatory movement of the latter in response to the movement of the platen. Thus the outer flange of member 49 swings in and out in relation to the angle 251 and is effective in engaging the end portions of the tickets, 10 thus jarring or jogging the same to assist the proper stacking of the tickets, particularly as they approach the lower part of the hopper. Thus the proper location of the lowermost ticket is assured so that this ticket may be engaged by the 15 feeding fingers 80 and advanced to printing position.

A sheet metal guide member 183 is secured to a part of the platen frame and affords an outstanding plate or straight bar portion extending 20 in the same general direction as the platen frame 37 when it is in printing position, but being inclined downwardly to a somewhat greater angle.

When tickets with string loops are disposed 25 within the hopper, these loops are placed over this bar portion of member 183 in the manner illustrated in Fig. 2. The outer end of the member 183 is bifurcated to provide an upturned prong 184 which is separated from the flat bar portion by a narrow slot. As a ticket passes to 30 printing position, the corresponding string loop tends to swing downwardly, and as the ticket leaves the printing position the loop engages the end portion of this slot, the knot at the end of the loop catching in the slot. Thus the ticket is 35 held on the machine after it leaves the printing position. When a plurality of tickets have been printed and are to be removed, their string loops may be disengaged from the member 183 by an upward movement to slide the loops out of the 40 slot provided by that member.

In the practical operation of a machine of this character, the carriage C is manipulated and the knob 119 is turned to effect the desired adjustment of the main printing wheels. This is done 45 until the group of symbols between bars 146^a corresponds to the characters that are to be printed on the main portion of the ticket. The knob 52 may then be adjusted in and out to permit the wheel 57 to be operatively connected 50 to successive auxiliary printing wheels and the corresponding indicating wheels. When the auxiliary indicating wheels 60 adjoining the indicator bar 73 afford a line of symbols corresponding to the price to be printed on the end of the ticket, 55 the auxiliary printing wheels 74 are properly adjusted. With the carriage C moved to its inoperative position, the main printing wheels are locked in position by the ribs 129 while the auxiliary printing wheels 74 are held in place by the 60 ribs on bushings 82 and 83, the wheel 72 remaining in engagement with one of these wheels and being held against rotation by the pawl or detent element 90.

A plurality of tickets of the desired size, i. e., 65 having one or more sections, may then be disposed in the hopper. One of these tickets provided with two sections is shown in Fig. 4, this ticket having one end section with a knotted string loop secured thereto and having an adjoining section separated from the first section by a perforated line. A pair of feed slots 104 may be disposed in this perforated line, being arranged for engagement with the feeding fingers 80. A ticket 70 of this general type is more fully disclosed in my copending application Serial No. 652,467, filed 75

January 19, 1932. The ticket may conveniently be provided with a vertical line 107 separating the main portion of each section from the end portion which is to receive the price indication, the main portion of each section being wide enough to receive the main group of symbols indicating the purchase price, lot, quality, source of supply, etc. 5

In practice the size of the hopper may be adjusted due to movement of the plate 252 to accommodate tickets having different numbers of sections. When tickets having two or more sections are provided, string loops may be employed on more than one section, if desired. When the tickets are disposed in the hopper, the weight 15 253 is lifted and disposed over the uppermost ticket. Thus the weight is effective in yieldably urging the tickets downwardly to the region of the feeding fingers 80. The string loops 103 of the tickets have their end portions disposed over 20 the outer edge of the straight bar or plate portion of member 183, as shown in Fig. 2.

The automatic stop mechanism S is then set to count the number of tickets being printed in accordance with the number of articles in the 25 lot to which the tickets are to be applied. If tickets each having two sections, for example, are to be printed, the drum 152 is adjusted until the number in the second column, corresponding to the number of tickets to be printed, is 30 disposed above the bar 155. If the motor 1 is not already running, the electric circuit is closed to start the motor in operation and the finger piece 174 is pressed inwardly to cause engagement of the clutch. Thus the main shaft 5 is 35 driven and the oscillatory movement of the platen frame 37 is effected through the linkage L as well as the feeding movement of the fingers 80. Thus successive sections of each ticket are 40 fed to printing position and successive tickets in turn are similarly fed beneath the printing platen 44. The weight 253 is effective in causing the movement of successive tickets downwardly to a position wherein they are engaged by the feeding fingers 80, which in turn engage the slots 45 104 and the edges of the tickets to feed successive ticket sections to printing position. 40

During each printing operation the platen 44 is effective in pressing one section of the ticket against ribbon 160 above the printing symbols 50 on the main printing wheels and in pressing the end portion of each section against the ribbon above the line of printing characters on the auxiliary printing wheels. As the tickets move out of printing position, the knotted string loops 55 catch in the slot at the end of member 183, and the tickets hang suspended from this member until removed.

As successive tickets are printed, the counting mechanism is effective in causing rotation of the 60 wheel 159 and of the drum 152 until the pin 164 upon the drum engages the clutch throwout block 165, moving the control rod 176 to a position corresponding to the disengaged position of the clutch. Thus the clutch is disconnected 65 and the main shaft 5 and linkage L is no longer driven in response to operation of the motor 1. Thus the desired number of tickets are printed.

Each ticket may be of the general type shown 70 in Fig. 4, with each section provided with a body portion having a transversely extending line or preferably two lines of staggered characters or symbols and having an end portion or zone with a price indication printed on its end, the direction of extent of the figures of the price being 75

transversely of the direction of extent of the main line or lines of characters and there being a blank space in the end zone to receive additional price indications when the price is changed 5 to conform to seasonal trends or other factors. This arrangement of the price indication upon the end of the ticket, with an adjoining blank space, is particularly advantageous, since it permits the cutting off of the extreme end of the 10 ticket bearing the original price indication and the application of a new price marking upon the original blank portion of the ticket. For this purpose a machine of the type disclosed in my copending application Serial No. 704,137 may 15 be conveniently employed.

It is evident that this invention affords a printing machine which is particularly adapted to facilitate the printing of price tickets in large or 20 relatively small lots for use in stores. When numerous articles of the same type or general character are to be marked but certain changes in the tickets are to be made, as changes in indication of size, the desired number of tickets for each size of garment may readily be printed 25 by proper setting of the stop mechanism S. The machine may then be stopped, the printed tickets for one size removed, and the necessary change in adjustment of one or two of the main printing wheels may then be quickly made and the 30 succeeding lot of tickets for the next size then be rapidly printed. It is evident that the automatic stop mechanism avoids necessity for counting tickets and the consequent possibility of mistake or error in counting, and furthermore, 35 avoids the liability of the wasting of tickets by printing too many tickets for a given lot of merchandise.

The arrangement of the oscillatory member 49 and of the guide and retainer 183 particularly 40 facilitates the printing of price tickets having string loops at their ends; the arrangement of the auxiliary printing wheels is advantageous in permitting a commercially convenient disposition of the printed matter upon the ticket so that 45 the price indication may readily be changed or entirely removed from the ticket and a new price indication applied without disturbing the information which should remain with the article throughout the period when it is on sale.

50 I claim.

1. Printing mechanism comprising a frame, a plurality of printing wheels mounted on the frame, a plurality of indicating wheels, means operatively to connect a selected wheel with a corresponding 55 indicating wheel to permit simultaneous adjustment thereof, said printing wheels being arranged to print a line of indicia, a set of auxiliary printing wheels, a set of corresponding auxiliary indicating wheels, and means selectively to connect 60 one of the auxiliary printing wheels and a corresponding auxiliary indicating wheel to permit adjustment of the auxiliary printing wheels, said auxiliary printing wheels being arranged to print the line extending transversely to the line printed 65 by the first-named printing wheels, and means cooperating with the printing wheels to effect a printing operation.

2. Printing mechanism comprising a supporting arbor, a plurality of printing wheels disposed 70 upon one end of the arbor, a corresponding set of indicating wheels disposed on the other end of the arbor and selectively operable means to connect one of the printing wheels with one of the indicating wheels to permit adjustment thereof, 75 said printing wheels being arranged to print a

line of characters extending in one direction, a set of auxiliary printing wheels mounted on a frame carried by the arbor and arranged to print a line of characters extending transversely to the first-named line and a set of auxiliary indicating wheels associated with the auxiliary printing wheels, and selectively operable means to permit adjustment of a selected one of the auxiliary printing wheels and the corresponding auxiliary indicating wheel. 10

3. Printing mechanism of the class described comprising a set of main printing wheels arranged to print a main line of characters extending in one direction, a set of auxiliary printing wheels arranged to print a line of characters extending transversely to the first-named line, supporting means for the main printing wheels and the auxiliary printing wheels, and means to permit selective adjustment of the auxiliary printing wheels, 15 said means including a slidable and rotatable shaft having a gear at its end, a second shaft having a gear meshing with the first-named gear, and means on said shafts to permit their simultaneous sliding movement, an element carried by the second shaft being engageable with a selected auxiliary printing wheel to permit adjustment thereof. 20

4. Printing mechanism of the class described comprising a set of main printing wheels arranged to print a main line of characters extending in one direction, a set of auxiliary printing wheels arranged to print a line of characters extending transversely to the first-named line, supporting means for the main printing wheels and the auxiliary printing wheels, means to permit selective adjustment of the auxiliary printing wheels, 30 said means including a slidable and rotatable shaft having a gear at its end, a second shaft having a gear meshing with the first-named gear and means on said shafts to permit their simultaneous sliding movement, an element carried by the second shaft to engage the auxiliary printing wheels to permit adjustment thereof, said first-named shaft having a plurality of grooves therein, and a spring-pressed plunger engageable with said grooves and effective in tending to cause the shafts to stop in a position so that said element may be effective in engaging only one of the auxiliary printing 35 wheels. 40

5. Printing mechanism of the class described comprising a plurality of printing elements, a cooperating platen mechanism to effect relative movement of the platen and the printing elements to effect repeated impressions, a hopper, means to feed tickets from the hopper between the platen and printing elements, means to interrupt movement of the platen, counting mechanism selectively adjustable to cause the operation of said interrupting means to stop impressions by the platen after a determined number of such impressions have been made, said mechanism being in the form of a rotatable member, step mechanism movable in response to the successive movements of the platen to cause step by step rotary movement of the said member, and a part carried by 60 said member movable into engagement with a part of said interrupting means. 65

6. Printing mechanism of the class described comprising a plurality of printing elements, a cooperating platen mechanism to effect the movement of the platen toward and away from the printing elements to effect repeated impressions, a hopper, means to feed tickets from the hopper between the platen and printing elements, means to interrupt movement of the platen, counting 70 mechanism selectively adjustable to cause the operation of said interrupting means to stop impressions by the platen after a determined number of such impressions have been made, said mechanism being in the form of a rotatable member, step mechanism movable in response to the successive movements of the platen to cause step by step rotary movement of the said member, and a part carried by 75 said member movable into engagement with a part of said interrupting means.

mechanism selectively adjustable to cause the operation of said interrupting means to stop impressions by the platen after a determined number of such impressions have been made, said

5 means being in the form of a rotatable member, step mechanism movable in response to the successive movements of the platen to cause step by step rotary movement of the said member and a part carried by said member movable into engagement with a part of said interrupting mechanism, and an indicating drum associated with said rotary member and having a plurality of circumferential columns thereon arranged to indicate different numbers of tickets which may be printed when the tickets each have one or more sections to be printed by successive impressions of the platen.

10 7. Printing mechanism of the class described comprising a supporting arbor, a plurality of printing wheels, a set of indicating wheels, a control carriage operable selectively to connect one of the printing wheels with the corresponding indicating wheel and to permit simultaneous adjustment of the same, said printing and indicating wheels having internal teeth, pinions carried by the carriage having teeth engageable with the internal teeth of corresponding printing and indicating wheels, and means associated with said shaft to cause the stopping of the pinions in a position wherein the teeth of adjoining printing and indicating wheels may lie in mutual alignment to permit shifting of the carriage to facilitate the adjustment of adjoining wheels.

15 8. Printing mechanism of the class described comprising a supporting arbor, a plurality of printing wheels, a set of indicating wheels, a control carriage operable selectively to connect one of the printing wheels with the corresponding indicating wheel and to permit simultaneous adjustment of the same, said printing and indicating wheels having internal teeth and pinions carried by the carriage having teeth engageable with the internal teeth of corresponding printing and indicating wheels, means associated with said shaft to cause the stopping of the pinions in a position wherein the teeth of adjoining printing and indicating wheels may lie in mutual alignment to permit shifting of the carriage to facilitate the adjustment of adjoining wheels.

20 9. Printing mechanism of the class described comprising a supporting arbor, a plurality of printing wheels, a set of indicating wheels, a control carriage operable selectively to connect one of the printing wheels with the corresponding indicating wheel and to permit simultaneous adjustment of the same, said printing and indicating wheels having internal teeth and pinions carried by the carriage having teeth engageable with the internal teeth of corresponding printing and indicating wheels, means associated with said shaft to cause the stopping of the pinions in a position wherein the teeth of adjoining printing and indicating wheels may lie in mutual alignment to permit shifting of the carriage to facilitate the adjustment of adjoining wheels.

25 10. A machine for printing tickets such as price tickets each having two sections thereon, one of said sections being adapted to receive a line of printed symbols to be permanently retained on the ticket, the other section being arranged to receive a price marking extending transversely of the end of the ticket and providing a blank zone between said marking and said group of symbols, said machine comprising selectively movable main printing wheels to print said group of symbols and control means to permit the selective movement of different wheels to bring different characters thereon to printing position, and a plurality of auxiliary printing wheels and associated control means therefor to bring different selected symbols thereon to printing position to print a price indication in spaced relation and extending in a line at right angles to the line of characters on the main printing wheels which occupy the printing position, a movable platen, mechanism to drive the platen to cooperate with the main and auxiliary printing wheels in effecting repeated impressions, feeding means to feed successive tickets between the platen and wheels, and automatic counting and stop mechanism adjustable to permit the platen to make a plurality of impressions and then to interrupt further movement of the platen.

30 11. A machine for printing tickets such as price tickets each having two sections thereon, one of said sections being adapted to receive a line of printed symbols to be permanently retained on the ticket, the other section being arranged to receive a price marking extending transversely of the end of the ticket and providing a blank zone between said marking and said group of symbols, said machine comprising selectively movable main printing wheels to print said group of symbols and control means to permit the selective movement of different wheels to bring different characters thereon to printing position, and a plurality of auxiliary printing wheels and associated control means therefor to bring different selected symbols thereon to printing position to print a price indication in spaced relation and extending in a line at right angles to the line of characters on the main printing wheels which occupy the printing position, a movable platen, a driving motor, linkage connecting the driving motor and platen, feeding means to direct successive tickets to a printing position between the platen and wheels whereby successive impressions may be provided upon successive tickets as the platen is driven by the motor, a clutch associated with said linkage to disconnect the linkage from the driving motor, and adjustable clutch controlling means provided with a counting mechanism so that a plurality of impressions may be made by the platen, and the clutch may then automatically be disconnected to permit the making of a definite number of impressions on the tickets.

CARL A. FLOOD.
